UNITED STATES PATENT OFFICE.

WILLIAM EDWARD MOULTON, OF WATERVLIET, NEW YORK.

ATTACHMENT FOR DRILLS.

1,333,559.

Specification of Letters Patent.

Patented Mar. 9, 1920.

Application filed April 14, 1919. Serial No. 289,777.

To all whom it may concern:

Be it known that I, WILLIAM E. MOULTON, a citizen of the United States, residing at Watervliet, in the county of Albany and State of New York, have invented new and useful Improvements in Attachments for Drills, of which the following is a specification.

From experience I have found that bits, 10 employed in the ordinary construction of portable motor driven drills become very frequently broken because the bit is not held at a direct right angle with respect to its work. As no means is provided upon 15 such classes of drills for indicating the degree of angle at which the same enters its work, it is almost an impossibility to continuously drill straight holes.

Also from experience I have found that by 20 the employment of a gage in the nature of a spirit level, or, more properly speaking, to hingedly connect spirit levels one movable right angularly with respect to the other, that holes may be drilled either vertically or horizontally at a direct right angle with respect to the work operated on, so that twisting the drill in an attempt to direct the same, when the said drill has taken an indirect path will be entirely avoided and 25 as a result true holes may be easily drilled and danger of the breaking of the drills will be effectively overcome.

The object of the present invention is to produce a device of this character which 30 shall be of an extremely simple construction, which may be readily attached to drills of any ordinary class, and which will perform the functions for which it is devised with accuracy and with certainty.

40 The foregoing objects, and others which will appear as the nature of the invention is better understood, may be accomplished by a simple construction, combination and operative arrangement of parts, such as 45 illustrated by the accompanying drawings, in which:

Figure 1 is a view illustrating a drill provided with the improvement.

Fig. 2 is a sectional view approximately 50 on the line 2—2 of Fig. 1.

Fig. 3 is a sectional view approximately on the line 3—3 of Fig. 2, and illustrating the horizontal level in operative position.

The numeral 1 designates a pneumatic or 55 other power drill, and 2 the bit therefor.

On the body of the drill is secured my

improvement broadly indicated by the numeral 3. The improvement contemplates the employment of a flat body member 4, having its edges provided with hinged leaf portions 5, and these leaf portions are secured to the body of the drill. By providing the body of the improvement with the pivoted leaves the device may be attached to any ordinary construction of drills, 60 whether the bodies thereof are oval in cross section, square, rectangular or any other shape. The body 4 of the improvement, at one of the ends thereof has an outwardly arranged right angular extension in the nature of a lug 6, the said lug having a central notch or cut-away portion 7 and having a bore therethrough, and in this bore is arranged a spirit glass 8, the bubble in the said glass being arranged in the notch 7 70 when the drill bit is held vertical.

On the inner and straight face of the lug 6 is hingedly connected, as at 9 a block 10. This block is provided with a bore 11 within which is arranged a spirit bulb or glass 80 12. The block, upon its outer face is provided with a notch or opening 13, and through this opening the bubble in the glass or bulb is discernible when the block 10 is swung at a right angle with respect to 85 the lug 6 and the body 4, and when the bulb is in this position the bit is properly arranged for horizontal boring. In order to sustain the block 10 at a desired right angle with respect to the body 4 there is pivotally secured, upon the inner face thereof, as at 14 a prop member 15. The prop is designed to contact with the outer straight face of the body 4 when the block 10 is arranged right angularly with respect to the 90 said body and to be folded against the inner flat face of the block 10 when the block is swung against the body 4. The body 4 may be provided with a depression 16 to receive the prop and the head of the pivot 100 14 when the block is swung against the body 4. From experience I have found that the weight of the block is sufficient to retain the same against the body 4, but if desired suitable latching means may be employed 105 for this purpose, the latter being indicated by the dotted lines in Fig. 2 of the drawings and designated by the numeral 18.

It is thought, from the foregoing description, when taken in connection with the 110 drawings, the simplicity of the construction and the advantages thereof will be readily

apparent without further detailed description.

Having thus described the invention, what is claimed as new, is:—

- 5 1. In a device for the purpose set forth, a flat body member, pivoted attaching means on the edges thereof, a right angularly lug disposed on one of the ends of the body, said lug having an inner straight face,
- 10 10. a spirit bulb in the lug, said lug having a central notch communicating with the spirit bulb, a block hingedly secured to the inner face of the lug and designed to normally rest against the body, a spirit bulb in said
- 15 15. block, said block, upon its outer face having an opening communicating with the bulb, and a pivoted prop on the inner face of the block designed to contact with the body to hold the block at a right angle with
- 20 20. respect to the body.

2. In a device for the purpose set forth,

a flat substantially rectangular body member, hinged leaf members on the edges of the body and designed to be secured to a support, a right angularly disposed lug on one 25 of the ends of the body having a bore therethrough and a central notch communicating with the bore, a spirit bulb in the bore, said lug having an inner straight face, a block hingedly connected to the inner face of the 30 lug and designed to normally rest on the body, means for retaining the lug in said right angular position, a pivoted prop on the inner face of the block designed to be swung against the body at a right angle 35 with respect to the body, said block having a bore therein and having on its outer face an opening communicating with a bore, and a spirit bulb in the bore.

In testimony whereof I affix my signature. 40

WILLIAM EDWARD MOULTON.
